HYGROSCOPIC CONTROL ELEMENT

Frederic F. Bahnsen, Winston-Salem, N. C., assignor to The Bahnsen Company, Winston-Salem, N. C., a corporation of North Carolina

Application November 28, 1930, Serial No. 498,857

4 Claims. (Cl. 297—1)

This invention relates to a hygroscopic element for humidity control devices and to a method of manufacturing the same.

Hygroscopic elements in the form of multiple strands have been proposed from time to time, but in such elements the strands were of filamentary nature, usually silk threads or hair, and no attempt was made to secure a circulation of air between the strands or to constantly and automatically equalize the stresses on all of the strands. The several strands of the hygroscopic material take the form of elongated ribbons or strips which are so mounted in end frames that all strands are subjected to the same stress. It will be evident that a hygroscopic control device of this type will not operate in the intended manner if there is a variation in the effective lengths of the several strands and/or if the strands have different operating characteristics.

An object of the invention is to provide a method of manufacturing hygroscopic elements of the type including a plurality of spaced and parallel strands of a hygroscopic material in the form of a ribbon or strip.

A further object is the provision of a method of manufacturing hygroscopic elements of the type comprising a hygroscopic strip wound on a pair of spaced frames wherein each strand or element has exactly the same operating characteristics as every other element similarly assembled.

Another object of the invention is the provision of a hygroscopic element of the above type wherein all of the sections of the strip lie parallel and normally extend perpendicular to the principal planes of the end frames.

Other objects of the invention will appear from the following description taken in connection with the appended drawings wherein:

Fig. 1 is a view showing a hygroscopic element constructed according to the present invention.

Fig. 2 is a side elevational view showing a portion of the apparatus in the position in which it is placed at an early stage in the assembling operation.

Fig. 3 is a fragmentary side elevational view showing the apparatus as in a later stage,

Fig. 4 is a view similar to Fig. 2, with the apparatus as seen at the completion of the assembly operation,

Fig. 5 is a fragmentary plan view of the apparatus as shown in Fig. 3,

Fig. 6 is a fragmentary sectional view showing a detail, and

Fig. 7 is a view showing the handling member.

In Fig. 1 is shown a completely assembled hygroscopic element. The principal element of the end frame 1 is a channel member 2, the flanges 3 of which are each provided with a row of holes 4, corresponding holes in each row being disposed opposite one another. A pair of lugs 6 are bent up from the web 7 and provided with oppositely disposed holes 8 to form means for connecting the frame 1 with another portion of the humidity control device (not shown). A thin channel-shaped spring clip 9 having flanges 10 and provided with an opening 11 for accommodating the lugs 6, is fitted over the channel 2. A roller 13 is disposed in each pair of aligned holes 4 in the flanges 3, the rollers 13 being of a diameter substantially equal to the space between any two adjacent holes 4.

A second end frame 1', spaced from the first frame 1 and having the web 7' of the channel member 2' parallel to the web 7 of the channel member 2 of the first frame 1, is similar to the first frame 1 except as to the rollers and the arrangement thereof. The second frame 1' is provided with one more roller than the first frame 1, the two end rollers 14a, 14b being somewhat smaller than the intermediate rollers 13. The spacing of the holes 4' is such that if the frames 1, 1' are placed opposite each other, rollers of one frame are opposite the spaces of the other frame, except that the axes of the two smaller rollers 14a, 14b are opposite the outer lateral edges of the end rollers of the other frame, respectively.

A thin strip of hygroscopic material 15 (hereinafter referred to as "the strip") is secured at one end to one of the small rollers 14a and is wound over successive rollers 13, 13' of each end frame alternately and the other end is secured to the second small roller 14b. It will be seen that, due to the size and arrangement of the rollers, a line drawn perpendicular to the plane of either web and tangent to any of the intermediate rollers of the second frame, is also tangent to one of the rollers of the first frame. Thus all of the sections of the strip extending between the end frames are parallel and extend perpendicular to the planes of the webs.

In Fig. 2 is shown a pair of similar, oppositely disposed end frame clamps 16, 16' mounted on a base 17 and spaced at such a distance that the hygroscopic element will be of the desired length when assembled thereon.

The clamp 16 comprises an upstanding member 18 supported on the base between two parallel foot members 19 each provided with an up-

turned flat hook portion 20, a pair of parallel arms 21 each provided with a depending flat hook 22 and pivotally mounted on the upper end of the upstanding member 18, and a screw 23 extending 5 through the central portion of the upstanding member 18. The other clamp is of exactly the same construction.

Suspended over the midpoint between the clamps 16, 16', by a cord 24 passing over a set of 10 sheaves 25, is a roller frame 26 in which is rotatably mounted a roller 27 having substantially the same width as the strip 15 of hygroscopic material used in forming the element 1. A weight 27 hung on the other end of the cord 24 exerts a 15 lifting force on the roller frame 26.

Disposed in alignment with the clamps 16, 16' is a clip 28 for securing the end of a strip of paper and, between the clip 28 and the nearer clamp 16, is a U-shaped roller support 29 which 20 is adapted to rotatably support a guide roller 30 of sufficient length to guide the strip 15 of hygroscopic material.

Mounted adjacent the clamp 16' is a post 31 carrying a pair of horizontal blades 32, 33, 25 mounted for independent rotation about a vertical axis. The blades 32, 33 are so mounted that they may be moved in a manner similar to a pair of scissors, into a position one above the other with the lower side of the upper blade 32 30 overlying the upper side of the lower blade 33.

The strip 15 which is used in making the hygroscopic element may be formed from any one of several materials but it is preferred to use a 35 highly beaten paper which has been cut transversely of the web.

The method of assembling the unit is as follows:

The end frames 1, 1', with the rollers 13, 13', 40 14, removed and the flanges 10, 10' of the spring 45 clips 9, 9' pushed away from their positions over the holes 4, 4' (as shown in dotted lines in Fig. 5) are inserted in the clamps 16, 16' with the hooks 22, 22' engaging the ends of the webs 7, 7' and the clamping screws 23, 23' tightened 45 against the webs 7, 7' to secure the frames 1, 1' in place.

The lowermost roller 14a is inserted in the end frame 16' that takes the small end rollers and one end of the strip 15 is wound over the roller 50 14a and cemented to form a loop whereby the end of the strip 15 is secured to the roller 14a. The other end of the strip 15 is cemented to the 55 end of a waste strip 34 which is of substantially the same width as the strip 15 but which is formed of some less expensive material, such as strips of hygroscopic material which are defective and unsatisfactory for use in forming the element. The free end of the waste strip 34 is passed over the roller and secured in the clip 28. 60 The weight 27 exerts a pull on the cord 24 to raise the roller frame 26 and roller 27 whereby the web 35, consisting of the strip 15 and the waste strip 34, will be drawn taut and will be subjected to a continuous tensile stress of constant value.

A thin, rigid, paddle-shaped handling member 36 is laid against the web 35 with the narrow end directed downwardly and is moved toward the 65 end frame on the opposite side of the web 35 to push the web 35 ahead of it. When the handling member 36 reaches the end frame 1, it is depressed to force the web 35 below the lowermost holes 4 in the frame 1 and a roller 13 is inserted in this set of holes to hold a portion of the web 75 35 in a horizontal position (as shown in broken

lines in Fig. 2). The handling member 36 is then placed on the other side of the web 35 and moved toward the other end frame 16'. A second roller 13' is inserted in the frame 4' over the web 35 to hold the second section of the web 35 in a position parallel to the first section (as shown in Fig. 3).

These steps are repeated until all of the rollers have been inserted in their respective frames except the top roller 14b to which the end of the strip is to be secured. The lower blade 33 is then moved to a position transversely of and overlying the top section of the strip 15. The web 35 is moved toward the end frame 16' and the top roller 14b inserted in a manner similar to the insertion of the other rollers.

The web 35 is then introduced into the space between the arms of the roller support 29 and the guide roller 30 inserted to thereby hold that portion of the web 35 which lies between the guide roller 30 and the end frame 16' in a substantially horizontal position. Cement is applied to a small portion, adjacent the end roller 14b, of the upper surface of the top section of the strip 15 and the upper blade 32 is moved to a position directly above the lower blade 33 to thereby clamp together the two thicknesses of the strip 15. When the cement has hardened, the strip 15 is severed adjacent the joint and the blades 32, 33 removed. The screws 23, 23' are loosened and the spring 100 clips 9, 9' are "snapped" into the position (shown in full lines in Fig. 5) in which their flanges 10, 10' respectively engage the flanges 3, 3' of the channel members 2, 2' whereby the rollers 13, 13', 105 14a, 14b are retained in their respective positions 110 in the channel members 2, 2'. The element is now complete and is removed from the clamps.

It is desirable to "cure" the hygroscopic material in order that the element will retain for a long period the same operating characteristics. 115 The curing is effected by suspending the one end frame of the element from a stationary support, attaching such a weight to the other end frame as will subject the element to a tension of the same order as the normal operating tensions 120 and subjecting the element to an atmosphere of varying humidity for a period of from two to ten days, which relative humidity has at least as great a range of variation as the relative humidity to which the strip will be subjected during operation. 125 When the curing is completed, the element is ready for use in a humidity control device.

I claim:

1. An end frame for a hygroscopic element for use in humidifying apparatus, comprising a rigid 130 channel member, a plurality of parallel rollers arranged in a row and extending between the flanges of said channel member and means for retaining said rollers in said channel member.

2. The invention as set forth in claim 1, where- 135 in said retaining means comprises a resilient channel-shaped clip having its flanges provided with inwardly directed bends engaging the flanges of said channel member.

3. In the process of manufacturing hygroscopic elements for air conditioning apparatus, the steps which comprise connecting a strip of hygroscopic material between a pair of end frames in a plurality of return bends, and curing said strip prior to assembly in the air conditioning apparatus by 145 maintaining a predetermined tensile stress on said strip and subjecting said strip to an atmosphere of varying relative humidity.

4. In the process of manufacturing hygroscopic elements for air conditioning apparatus, 150

the steps which comprise winding a strip of hygroscopic material over a pair of end frames, securing one of said frames, suspending a known weight from the other of said frames to subject to an atmosphere of varying relative humidity having at least as great a variation as the relative humidity to which the strip will be subjected during operation.

5 said strip to a tensile stress of the same order as the operating stresses, and subjecting said strip
